UNITED STATES PATENT OFFICE.

CLAUDE D. SHELLABARGER, OF SPOKANE, WASHINGTON.

PUMP-EQUALIZER.

1,109,706.

Specification of Letters Patent.

Patented Sept. 8, 1914.

Application filed September 23, 1913. Serial No. 791,444.

To all whom it may concern:

Be it known that I, CLAUDE D. SHELLABARGER, a citizen of the United States, residing at Spokane, in the county of Spokane and State of Washington, have invented a new and useful Pump-Equalizer, of which the following is a specification.

My invention relates to improvements in pump equalizers in which springs are used to develop power on the up-stroke of a pump handle to aid in lifting the weight of the pump rod and fluid on the down stroke of the pump handle; and the objects of my invention are to provide a device to equalize the load between the up and down strokes that is simple in construction, that will not easily break or get out of order, and that can be quickly adjusted to increase or diminish the resistance of the springs. I attain these objects by the mechanism illustrated in the accompanying drawing, in which—

Figure 1 is a view of my complete device attached to a vertically reciprocating pump; Fig. 2 is a view of one portion of my device attached to the pump in a different position; Figs. 3 and 4 show the two forms detached; Fig. 5 is a top view of one of the lever arms; Fig. 6 is a view of the upright standard connecting a pair of the lever arms; Fig. 7 is an elevation of the end of Fig. 6; Figs. 8 and 9 are bearings for the lever arms.

Similar characters refer to similar parts throughout the several views.

Referring to the drawing, 1 is the stem or rod of a pump 2 reciprocating through bearing 3 attached to the body of the pump. Supported by this bearing is a collar 4 through which the pump rod 1 reciprocates, and a ring 5 is attached to the rod by a pin. The collar 4 and ring 5 have oppositely disposed recesses 6 to receive the teeth 7 of the lever arms 8. The lever arms 8 are ful-

crumed in pairs on the standards 9, each pair of lever arms being connected at their outer ends by a bolt 10 passing through holes in the lever arms, enlarged so as to allow of a free movement of the arms. At the ends of the bolt 10 are spiral springs 11, the tension of which may be adjusted by the nut 12.

It will be observed that when the pump handle 13 is down, the position of the lever arms 8, as in Fig. 1, allows the springs 11 to expand, and when the pump handle 13 is raised, the inner ends of the upper and lower lever arms 8 are brought together and the outer ends separated, thus compressing the springs, which react on the lever arms to raise the pump rod when the pump handle is forced down.

Having thus described my invention, what I claim as new and desire to secure by Letters Patent is—

1. The combination with a pump having a reciprocating rod, of lever arms fulcrumed between their ends in pairs, the outer ends of the arms having springs adapted to be compressed by the movement of the arms, one of the lever arms being attached to a bearing on the pump and the other to a bearing on the pump rod.

2. The combination with a pump having a reciprocating rod, of lever arms fulcrumed between their ends in pairs, the outer ends being slidably mounted on a bolt having its ends inclosed by springs, one of the lever arms being attached to a bearing on the pump and the other to a bearing on the pump rod, the said springs being adapted to be compressed by the action of the levers.

CLAUDE D. SHELLABARGER.
